UNITED STATES PATENT OFFICE

HANS F. MAHLSTEDT, OF GILMAN, IOWA

HOG TROUGH

Application filed April 7, 1928. Serial No. 268,202.

My invention relates to a trough to be used for feeding or watering animals, especially hogs, and has for its object to provide a trough of the type disclosed in the issued 5 patent of Alfred J. Jahde, #1,531,617, issued March 31, 1925.

More specifically, it is my object to provide a trough of this type having means for securing it to a stationary support so as to 10 prevent tipping and to simplify and cheapen the construction of such a trough without sacrificing durability or strength.

Another object of my invention is to provide a trough, the walls of which may be 15 made in three pieces, a reinforcing member being provided, adapted to permanently secure the three pieces together and adapted also to provide means for supporting the trough rigidly upon a stationary support. 20 Thus the supporting members become an integral part of the trough and the construction of the trough is clearly simplified.

With these and other objects in view, my 25 invention consists in the construction, arrangement and combination of the various parts of my device, whereby the objects contemplated are attained, as hereinafter more fully set forth, pointed out in my claim, and illustrated in the accompanying drawings, in 30 which:

Fig. 1 is a perspective view of the preferred form of my invention installed in connection with a stationary support.

Fig. 2 is a plan view of the trough.

Fig. 3 is a transverse, sectional view, taken on the line 3—3 of Fig. 1.

Fig. 4 is a similar sectional view, showing a somewhat modified form of my invention.

The two end walls 10 of the trough are 40 substantially triangular shaped, as clearly illustrated in the drawings, with their rear edges vertical, as at 11, and their forward ends inclined inwardly and outwardly, as 45 at 12. The upper edges of the end walls 10 are rolled outwardly and around the side arms 13 of the longitudinal yoke, which is a U shaped member formed of a piece of heavy steel wire, joined with the three portions 13 50 and 14 at right angles to each other.

The reinforcing member forms the structural framework of my trough.

A single, rectangular sheet of material is employed to form the front and rear walls 15 and 16, respectively, which are connected 55 by a curved bottom. The rear wall 16 is vertical and the front wall 15 is inclined at the proper angle to correspond to the forward edges 12 of the end walls 10. The upper edge of the forward wall 15 is rolled outwardly around the member 14 of the reinforcing yoke and the upper edge of the rear wall 16 is rolled around a cross member 17, which is formed of wire and secured at its end to the arms 13 of the yoke. As shown 65 in the drawings, the preferable method of securing is by looping the ends of the cross member 16 about the side arms of the yoke.

The edges of the end walls 10 and the walls 15 and 16 are joined together by any 70 method such as by folding, crimping, soldering or welding. Almost any water-tight joint will be sufficient for the reason that the strains to which the trough will be subjected are borne by the wire reinforcing 75 members almost entirely. Since a hog trough receives very rough usage, this is an essential feature of my invention.

One of the requirements for a hog trough is that it shall be secured so that it cannot 80 be tipped over by the hog. The hog, in rooting with his snout, is capable of exerting considerable pressure.

In order to attain maximum strength, I 85 form the elements by means of which the trough is secured to a stationary support, as integral continuations of the reinforcing yoke. The side arms 13 are extended beyond the cross brace 17, as at 18 and in the preferred form of my invention are bent 90 downwardly to form hooks 19, adapted to be received in vertical openings 20 in a stationary support 21, such as a horizontal rail of a fence or a portion of a gate or a hog house or the like. The hook 19 is made 95 parallel to the rear wall 16 so that the wall 16 may abut flatly against the member 21. In this way, should the hog put its feet into the trough and allow its weight to rest in the trough, the pressure will be borne partly by 100

the hook 19, partly by the extended arms 18 and partly by the rear wall 16.

Upward pressure of the snout of the hog against the trough will be borne entirely by 5 the hook 19.

In the modified form of my invention, shown in Fig. 4, the arms 18a are made long enough to extend clear through the stationary support 21a and at their ends are curled 10 to form rings 22, through which pins 23 are inserted to engage the rear face of the stationary members 21a. Upward pressure in this case is borne by the arms 18a, engaged against the upper limit of the slot 23 in the 15 support 21a. The slot 23 is made large enough to allow entrance of the rings 22.

No matter where the hog may apply pressure to the trough, this pressure will be transmitted directly to the reinforcing yoke, 20 forming an integral part of the trough and hence to the integral arms of the yoke. There will be no possibility of loosening the joints at the corners of the trough or loosening the connection of the supporting arms with the 25 trough. At the same time, the construction is simplified and cheapened. The walls may be first secured to the yoke and then soldered together, the yoke acting to retain them in their proper relationship. The necessity of 30 firmly securing the supporting arms to the trough is eliminated.

Some changes may be made in the construction and arrangement of the parts of my invention without departing from the 35 real spirit and purpose of my invention, and it is my intention to cover by my claim, any modified forms of structure or use of mechanical equivalents, which may be reasonably included within their scope.

40 I claim as my invention:

In a trough of the class described, a front, bottom and rear walls formed in one piece, side walls joined to the side edges of the same, a reinforced yoke, the upper edges of 45 the front and side walls being secured to said yoke, a reinforcing cross piece secured at its ends to the side arms of said yoke, the upper ends of the rear wall being secured to the crosspiece; the ends of the side arms of said 50 yoke being projected rearwardly to form supporting arms, to be received through a pair of horizontal openings in a supporting wall and eyes formed on the ends of said supporting arms in positions to receive pins 55 engaging the surface of said supporting wall opposite the trough, the rear wall being positioned vertically to engage the adjacent surface of said supporting wall, whereby said trough may be supported by the engagement 60 of said pins against the supporting wall and the engagement of said rear wall against the supporting wall.

Signed this 26 day of March, 1928, in the county of Woodbury and State of Iowa.

65 HANS F. MAHLSTEDT.
